MITT

No. 14,581

January 29, 1884.

UNITED STATES PATENT OFFICE.

WARREN P. JENNINGS, OF BROOKLYN, NEW YORK.

DESIGN FOR A MITT.

SPECIFICATION forming part of Design No. 14,581, dated January 29, 1884.

Application filed November 26, 1883. Term of patent 7 years.

To all whom it may concern:

Be it known that I, WARREN P. JENNINGS, a resident of Brooklyn, in the county of Kings and State of New York, have invented and 5 produced a new and original Design for Ladies' Mitts, of which the following is a full description, in connection with the accompanying photograph, which represents a face view of my new design for a mitt.

10 This invention relates to a new design for ladies' mitts; and it consists in the arrangement of apertures that form figures for ornamenting the mitt, as hereinafter more fully described.

At the upper end the mitt A has a series of 15 rectangular figures, a. Below this series of figures a is another series of rectangular figures, b, each figure being composed of small dots or holes. Below this series b is a series of longer

rectangular figures, d, below which is another series of shorter rectangular figures, e. Below this are stripes f, between which are the hexagonal figures g. The lower end of the mitt is ornamented by stripes h and intervening hexagonal figures i.

I claim—

- 25 1. The design for a mitt, the same consisting of the figures a, b, d, e, f, and g, substantially as shown.
2. The design for a mitt, the same consisting of the figures a, b, d, e, f, g, h, and i, substantially as shown.
